UNITED STATES PATENT OFFICE

2,138,742

MEASURING DEVICE

Vernon D. McBrayer, Phil Campbell, Ala.

Application June 10, 1938, Serial No. 213,043

2 Claims. (Cl. 221—113)

My invention relates to measuring devices for use in the measuring of semi-liquids or comminuted solids that are passed through chutes, measuring heads and the like and has for one of its principal objects the measuring of a predetermined amount of the materials and depositing the same therefrom into bags or other suitable containers.

Another object of my invention is to provide a device of the above described character equipped with adjustable means wherein the amount of the materials measured may be readily varied.

A further object of my invention is to provide a device of the above described character which is simple in construction, positive in operation, efficient in use and economical in manufacture.

Other objects and advantages will be apparent from the following description, appended claims and annexed drawings.

Referring to the drawings wherein like reference characters designate like parts throughout the several views:

Figure 1 is a side elevation of my invention, several of the parts being illustrated in section.

Figure 2 is a longitudinal sectional view of my invention illustrating another position of the parts.

Figure 3 is a detail sectional view taken on the line 3—3 of Figure 1.

Figure 4 is a detail sectional view taken on the line 4—4 of Figure 2.

Figures 5 and 6 are detail sectional views taken on the lines 5—5 and 6—6 of Figure 1 respectively.

Figure 7 is a detail sectional view of the lower end of the chute.

Figure 8 is a detail side elevation of the pedal employed for operating my device.

Figure 9 is a modified form of chute construction.

Figure 10 is a view similar to Figure 9 illustrating the closure in another position.

In practicing my invention, with particular reference to the preferred embodiment illustrated in Figures 1 to 8 inclusive, I provide a frame 5 having top, side and bottom walls 6, 7 and 8 respectively, the bottom wall being adapted to rest upon a table 9 or other suitable support. Extending through the top wall 6 within the frame 5 is a chute structure 10 formed with a material discharge passage 10a extending therethrough and having upper, lower and intermediate sections 11, 12 and 13 respectively of substantially square configuration in cross section. The upper

section 11 has secured thereto a depending support member 14 and which is attached to the top wall 6 by means of a transversely extending angle iron 15.

The lower end section of the support member 14 is fashioned with an elongated slot 16 adjustably receiving a bolt 17 secured through the adjacent wall of the lower section 12 and said bolt is provided with a wing nut 18 whereby to clamp the lower section in an adjusted position to the member 14. The upper end of the intermediate section 13 is fixed within the lower end of the upper section 11 while the lower end of the intermediate section is slidably adjustable relative to the upper end of the lower section 12 as clearly illustrated in Figure 2, consequently the lower section 12 may be adjustable relative to the upper section 11 through the medium of the bolt 17 operating in the slot 16.

As illustrated in Figures 2, 3 and 4, a wall 11a of the upper section 11 is slotted throughout the width thereof as likewise is the adjacent portion of the member 14 whereby to receive therethrough a slide closure 19 and the oppositely disposed wall 11b of said section is provided with spaced slots 21c through which extend a pair of spaced arms 20 integrally formed with the closure 19, the outer ends of said arms being integrally connected by a transverse section 21. Said arms 20, closure 19 and section 21 coact to define a substantially square shaped opening 22 adapted to permit the passage of material from the upper end of the upper section 12 to the lower end thereof when the closure 19 is in open position as illustrated in Figure 3. When the closure is in closed position, as illustrated in Figure 4, the opening 20 is disposed exteriorly of the upper section and communication between the upper and lower ends of the upper section is closed.

It is to be noted that the faces of the closure 19 and section 21 defining the opening 22 serve to abut the embraced section of the wall 11b and limit the opening and closing positions of the closure 19. One end of the closure 19 has connected thereto a U-shaped member 23 to which one end of a spring 24 is secured. The opposite end of said spring is connected to a bolt 25 mounted within the lower end of a depending bracket 26 secured to the top wall 6.

A nut 27 is secured to the outer end of the bolt 50 and adjustable thereon for varying the tension of the spring 24. The spring 24 serves to normally urge the closure 19 to open position as illustrated in Figures 1 and 3. The opposite end of the closure 19 has secured thereto a similar 55

U-shaped member 28 having attached thereto one end of a cable 29 trained over a pulley 30 supported by a bracket 31 mounted on the top wall 6. The opposite end of the cable 29 has secured thereto the upper end of a spring 32 and the lower end of said spring is connected to the upper end of a rod 33 extending downwardly through an opening 34 formed in the bottom wall 8 of the frame. The lower end of said rod is connected to a pedal 35 pivoted to a supporting bracket 36 fixed to the floor or the like.

Secured to the inner face of the side wall 7 there is a bracket 37 having a horizontally disposed end pivotally connected as at 38 to a lever 39 adjacent the outer end thereof. The inner end of said lever is pivotally connected to an upwardly extending rod 40 on which is adjustably mounted a sleeve 41 having a horizontally extending section 42 on which is pivoted the upper end of an arm 43. The lower end of said arm 43 is angularly disposed relative to the upper end thereof and is fashioned with an arcuate section 44 engaging the outer face of a gate 45 secured to said arm by means of a bolt extending through said arcuate shaped section. A spring 46 is secured about said bolt and is interposed between said arcuate shaped section and a nut secured on the outer end of the bolt and coacts therewith to maintain the outer face of the gate 45 in yielding engagement with the arcuate section 44. One end of the gate 45 is equipped with a pin 48 extending through the arm 43 to prevent lateral displacement of the gate relative to the arm.

Intermediate of the ends thereof the arm 43 has pivoted thereto the lower angularly disposed end of a bracket 49 secured to the outer face of the lower section 12 and said bracket is fashioned with an upper horizontally disposed portion 50 through which extends a rod 51 pivotally connected at the lower end thereof to the arm 43 as at 52. The rod 51 adjacent the lower end thereof is provided with a collar 53 for engagement with the lower end of a spring 54 mounted about said rod, the upper end of said spring engaging the under face of the portion 50 whereby to normally urge the arm 43 away from the portion 50 to effect closing of said gate.

The lower end of the lower section 12 is mitered for engagement with the inner face of the gate 45 as clearly illustrated in Figure 2. Said lower end is also provided with a housing 57 extending therebelow and fashioned with a lower reduced section 58 whereby to receive thereover the mouths of containers, bags and the like for filling by material discharged through the chute.

Secured on the rod 33 between the spring 32 and lever 39 is an adjustable sleeve 56 for engagement with the outer end of the lever 39 whereby the gate 45 is operated to open position. The upper end of the section 11 is provided with a hopper 57 for receiving material to be discharged through the passage 10a of the chute.

In operation of the closure 19 is normally maintained in open position and the gate 45 in closed position as illustrated in Figures 1 and 3. In this position material from the hopper fills the chute and is ready for discharge through the housing 57 upon opening of the gate 45. Operation of the pedal 35 through the medium of the rod 33 and cable 29 serves to move the closure 19 to the closed position as illustrated in Figure 4 and thereby shuts off material in the passage 10a above the closure 19. Continued operation of the pedal causes further downward movement

of the rod 33 against the tension of the spring 32 and effects engagement of the sleeve 56 with the outer end of the lever 39 thereby causing pivotal movement of the arm 43 through the medium of the rod 40 and bracket 49. The pivotal movement of the arm 43 serves to retract the gate 45 from engagement with the lower end of the lower section 12 thereby permitting discharge of material from the passage 10a through the reduced section 55 of the housing and into a container or the like. Upon release of the pedal 35, the rod 33 moves upwardly and releases the sleeve 56 from the end of the lever 39 thereby effecting closing of the gate through the medium of spring 54. As the rod 33 moves upwardly the spring 32 contracts and permits the spring 54 to move the closure 19 into open position. From the foregoing it will be apparent that a predetermined amount of material is contained within the chute between the closure 19 and gate 45 and that by adjusting the lower section 12 relative to the upper section 11, the amount of material to be discharged may be varied.

In the modified form illustrated in Figures 9 and 10 the upper portion of the upper section 11 is fashioned with an enlarged passage 60 and a horizontally disposed seat 61 for accommodating the closure 62 thereby enabling the closing of the gate 45 subjacent the lower section 12 in advance of the opening of the passage 60. In this construction, the spring 32 is eliminated and the upper end of the rod 33 is connected directly to the lower end of the cable 29.

What I claim is:

1. A device of the character described, comprising, a frame, a chute mounted in said frame and provided with upper and lower relatively adjustable sections, means for maintaining said sections in a predetermined adjusted position, upper and lower closures for said upper and lower sections respectively and functioning to measure the quantity of material discharged from said chute upon operation of said lower closure, a cable connected to said upper closure for moving the latter into closed position, a spring connected to said upper closure for normally urging the latter into open position, an arm pivotally mounted on said lower section and connected to said lower closure whereby to actuate the latter to open and closed positions, a rod extending within said frame and equipped with a sleeve, a lever pivotally mounted on said frame for effecting connection between said arm and sleeve upon movement of said rod in one direction whereby said lower closure is actuated to open position, and a sleeve connecting said cable to said rod for effecting movement of said upper closure to closed position in advance of movement of said lower closure to open position.

2. A device of the character described, comprising, a frame, a chute mounted in said frame and provided with upper and lower relatively adjustable sections, means for maintaining said sections in a predetermined adjusted position, upper and lower closures for said upper and lower sections respectively and functioning to measure the quantity of material discharged from said chute upon operation of said lower closure, a cable connected to said upper closure for moving the latter into closed position, a spring connected to said upper closure for normally urging the latter into open position, an arm pivotally mounted on said lower section and connected to said lower closure whereby to actuate the latter to open and closed positions, a rod extending within said

frame and equipped with a sleeve, a lever pivotally mounted on said frame for effecting connection between said arm and sleeve upon movement of said rod in one direction whereby said lower closure is actuated to open position, a sleeve connecting said cable to said rod for effecting movement of said upper closure to closed position

in advance of movement of said lower closure to open position, and means connected to said arm for actuating said lower closure to closed position in advance of the movement of said upper closure to open position.

5
